UNITED STATES PATENT OFFICE.

ARISTOTE MAVROGENIS, OF MILWAUKEE, WISCONSIN.

ELECTRON-DISCHARGE DEVICE.

Application filed September 16, 1926. Serial No. 135,817.

This invention relates to electron discharge devices.

This invention is an improvement over those disclosed in the following patents issued to me: No. 1,570,444, of January 19, 1926, for wireless apparatus, and No. 1,616,914, of February 8, 1927, for electron discharge device, and is also an improvement over the invention disclosed in my co-pending application, Serial No. 78,876, filed January 2, 1926.

Further objects of this invention are to provide a novel form of electron discharge device combining as a unitary member a full wave rectifier, a current limiting device and an audion, and so constructed that the condenser used as storage condenser can be materially reduced in size with consequent reduction in cost and reduction in the size of the device itself, if need be, or else to provide for the material increase in output of the device.

Further objects are to provide a device having the characteristics enumerated above which is adapted to be directly connected to the usual alternating current lighting circuits so that it will be supplied directly from the circuits without the intervention of a step-up or step-down transformer and without the use of a resistance bridged across the mains to furnish the usual neutral point.

It is the usual practice in full wave rectification to provide a transformer in which the neutral point is furnished by means of the center point of the secondary, or else to provide a resistance connected across the mains and to locate the neutral point at the center point of the resistance.

Both of the schemes noted above result in an increase in the cost of a device and require auxiliary apparatus. For example, if the resistance is placed in the tube itself it markedly interferes with the operation of the elements of the tube, due to the heat liberated in the tube. Further the voltage drop is necessarily high through the device and through the resistance with consequent loss in power and efficiency.

This invention is designed to overcome the defects enumerated above, and other objects of this invention are to so construct the electron discharge device that it may be directly connected to the alternating current

mains without employing either a transformer or a resistance and without increasing the cost of the device.

An embodiment of the invention is shown in the accompanying drawings, in which:

Figure 1 is an enlarged view of the tube 60 with parts broken away for clearness.

Figure 2 is a transverse sectional view approximately on the line 2—2 of Figure 1.

Figure 3 is a sectional view approximately on the line 3—3 of Figure 1, showing the 65 condenser with parts broken away.

Figure 4 is a fragmentary view of the cathodes and filament, such view being partly in section.

Figure 5 is a diagrammatic view showing 70 one form of the tube connected in a circuit.

Figure 6 is a similar view showing a slightly modified form of tube.

Referring to the drawings, particularly Figures 5 and 6, it will be seen that the 75 tube comprises a main evacuated vessel 1 carried by a base 2. In the diagram the upper portion is to be understood as the evacuated space and the lower portion as the base. This construction is more clearly 80 indicated in Figure 1, from which it will be seen that the tube body 1 is of the usual contour on its outer side and the base 2 is substantially like the conventional type of 85 vacuum tube base.

The tube is provided with a filament 3 which is connected to the prongs 4 and 5 of the tube and from thence through a variable resistance 6 to the alternating current mains 7 and 8.

The filament heats the cathode 9 of the full wave rectifier, the cathode 10 of the current limiting device, and the cathode 11 of the audion.

It is to be noted that the anodes 12 and 95 13 of the full wave rectifier are connected to opposite ends of the filament within the tube and are thus connected to the prongs 4 and 5.

Further it is to be noted that the anode 100 14 of the current limiting device is connected to the cathode 9 of the rectifier and the cathode 10 of the current limiting device is connected to the plate or anode 15 of the audion, the grid 16 being interposed between the plate 15 and the cathode 11. It is to be noted that the grid 16 is provided with a 105 prong 17 and that the cathode 11 is similarly

provided with a prong 18. Further, it is to be noted that a fifth prong 19 is connected to the middle point of the filament and is connected through the out-put circuit consisting of a primary 20 to the cathode 11. Further, it is to be noted that the grid is connected to the cathode 11 of the audion through the secondary 21 of the in-put transformer.

10 It is to be particularly noted that a storage condenser 22 is connected between the cathode 9 of the rectifier and the center point of the filament 3. Further, a bypass condenser 23 is connected between this center 15 point of the filament and the anode or plate 15 of the audion. These connections are made within the tube or within the tube base, in actual practice.

10 In operation it will be seen that the three 20 cathodes namely 9, 10, and 11, of the rectifier, current limiting device and the audion, are heated by the filament. Further it is to be noted that the anodes 12 and 13 of the rectifier are connected to the mains 8 and 7 25 respectively.

Considering for an instant the condition when the main 8 is positive and the main 7 negative, it will be seen that current passes from the anode 12 of the rectifier to its cathode 9. From thence it passes to the anode 14 of the current limiting device, and from the cathode 10 of the current limiting device it passes to the plate 15 of the audion. From this point current passes to the cathode 11 of the audion through the primary 20 and to the middle or neutral point of the filament.

It is to be noted that the condenser 22 acts as a storage condenser as it is connected 40 between the cathode 9 of the rectifier and the center point of the filament, and consequently is charged and gives up a portion of its charge during each half cycle. Further, considering the condition when the main 7 is positive and the main 8 negative. In this case current passes from the anode 13 of the rectifier to the cathode 9 thereof and from thence follows the circuit previously traced. Consequently the condenser 50 22 is again charged during the half cycle. The current limiting device, however, at all times holds the current value to a predetermined point so that no fluctuation can occur in the current delivered from the current limiting device. However, it is to be noted that the storage condenser 22 may be 55 made very much smaller than in my previously mentioned invention, as the rectifier is a double wave rectifier. Further it is to be noted that no transformer is required with this type of tube as the connections are such that the center point of the filament is utilized as the neutral point.

60 It is to be noted further that the bypass condenser 23 allows for variations in the

current flow through the audion as the current flowing through this portion of the device depends upon the incoming signals.

It will be seen that the condensers 22 and 70 23 have a common point and consequently may be built up as a single block, as indicated at 24 in Figure 1, the common point of the condensers being connected to the prong 19.

It will be seen further that this device 75 provides for the use of a very much smaller storage condenser than has heretofore been possible, and further that the filament operates in a dual capacity, namely, to heat the various cathodes and at the same time 80 to furnish a neutral point for the return of the audion current.

In the form shown in Figure 6 the tube and base are identically the same as in Figure 5 and the circuits are the same, except for the fact that the by-pass condenser 23 is bridged by the by-pass resistance 25. This resistance acts in conjunction with the condenser 23 and bypasses a portion of the current supplied the audion to thus further 90 provide for fluctuation in the current passing through the audion in accordance with the received wireless waves.

It is to be noted that the temperature of the filament is controlled by the variable 95 resistance 6 and further it is to be noted that the voltage impressed upon the plates of the apparatus is simultaneously controlled by this resistance. Thus the control of the tube is reduced to a single element. 100

The actual construction of the tube is indicated in Figures 1, 2, 3, and 4. It will be seen that the tube 1 is provided with a reduced neck 26 which fits within the base 2 and is cemented therein in the usual manner. Preferably immediately below the neck 26 of the tube a mica washer 27 is positioned to prevent the cement from finding its way into the lower portion of the base. Within this lower portion of the base 110 105 the condenser block 24 is positioned, such condenser block including, as stated above, the condensers 22 and 23.

The construction of the heater is indicated in Figure 4, from which it will be seen 115 that the filament 3 is carried within porcelain or quartz tubes 28 and has connections at its center and terminal points. The quartz tubes 28 are arranged in a substantially V-shape. They are surrounded at 120 their upper ends by metal tubes, such as tungsten tubes, for instance, which constitute the cathode 11 of the audion. At its lower ends it is surrounded by metal tubes, such for instance as tungsten, which constitute the cathode 10 of the current limiting device and the cathode 9 of the rectifier. 125

The plate 15 of the audion is preferably carried in the upper portion of the apparatus by means of suitable supports, as 130

shown in Figure 1, and the grid 16 is positioned within this encircling plate and carried preferably by the supports indicated at 29 in Figure 1. In order to space the 5 side strands of the grid from the cathode of the audion, preferably an additional rod 30 is secured to each of the supports 29, as shown in Figure 1. The center point of the filament is connected to the member 31, (see 10 Figure 1) and from thence by means of a suitable support to the prong 19.

The plates 12 and 13 of the rectifier are carried by suitable supports and are held in spaced relation to the cathode 9 to such 15 rectifier. The plate 14 of the current limiting device is preferably U-shaped and is carried by a forked support 32, (see Figure 1.) This support is connected by means of the conductor or bar 33 to the cathode 9 20 of the rectifier.

The supports are all sealed within a glass bridge piece 34 which extends downwardly and is joined at the base of the tube to the envelop or enclosing body portion of the 25 tube.

It will be seen that a very effective and compact device has been provided by this invention, in which relatively small condensers may be employed and are carried 30 within the base of the tube so that the tube forms a unitary device complete in itself.

Further, it will be seen that the tube may be constructed with scarcely any greater expense than the usual types of vacuum 35 tube, although it embodies means for direct connection to commercial alternating current lighting mains and does not require the use of a condenser, a resistance, choke coils, or other auxiliary apparatus.

40 It is to be noted further that even if the tube is connected to a direct current, commercial, or ordinary lighting main, it will still function in a satisfactory manner, as one or the other of the plates 12 or 13 of the rectifier will be connected to the positive 45 main, and, consequently, correct operation of the tube will result.

It will thus be seen that the tube is capable of universal use with either type of 50 supply main, and, as stated, does not require the use of auxiliary apparatus of any nature.

It is to be noted that the rectifier current flows alternately through opposite halves of 55 the heater and, consequently, adds its minute heating effect to the heater so that no waste occurs. This effect, however, is so small and is so rapid that there is no appreciable or noticeable result from such rectified current flow through the heater. In addition to this, the mass of the several cathodes and of the insulating tube maintains 60 a constant and even temperature.

Although the invention has been described 65 in considerable detail, such description is in-

tended as illustrative rather than limiting as the invention may be variously embodied and as the scope of such invention is to be determined as claimed.

I claim:

70 1. A unitary electron discharge device comprising an evacuated vessel having a full wave rectifier provided with a pair of plates and a cathode, a current limiting device provided with a plate and a cathode, the plate of the current limiting device being connected to the cathode of the rectifier, and an audion having a plate and a cathode and an interposed grid, the plate of the audion being connected to the cathode of the current limiting device, a heater for said cathodes, and a connection leading to the center point of the heater.

80 2. A unitary electron discharge device comprising an evacuated vessel having a full wave rectifier provided with a pair of plates and a cathode, a current limiting device provided with a plate and a cathode, the plate of the current limiting device being connected to the cathode of the rectifier, and an audion having a plate and a cathode and an interposed grid, the plate of the audion being connected to the cathode of the current limiting device, a heater for said cathodes, and a connection leading to the center point of the heater, the plates of 90 the rectifier being connected to opposite ends of said heater.

95 3. A unitary electron discharge device comprising an evacuated vessel enclosing a rectifier, a current limiting device and an audion, said rectifier having a cathode and a pair of plates, said current limiting device having a cathode, and a plate connected to the cathode of the rectifier, said audion having a cathode, a grid and a plate with the plate connected to the cathode of the current limiting device, a heater for said cathodes, and a storage condenser connected between the center point of the heater and the cathode of the rectifier, the plates of said rectifier being connected to the ends of said heater.

100 4. A unitary electron discharge device comprising an evacuated vessel enclosing a rectifier, a current limiting device and an audion, said rectifier having a cathode and a pair of plates, said current limiting device having a cathode and a plate connected to the cathode of the rectifier, said audion having a cathode and a plate and a grid with the plate connected to the cathode of the current limiting device, a heater for said cathodes, and a storage condenser connected 105 between the center point of the heater and the cathode of the rectifier, the plates of said rectifier being connected to the ends of said heater, said device having five prongs, 110 two of the prongs being connected to the terminals of the heater and the plates of 115 said rectifier being connected to the ends of said heater, said device having five prongs, 120 two of the prongs being connected to the terminals of the heater and the plates of said rectifier being connected to the ends of said heater, said device having five prongs, 125 two of the prongs being connected to the terminals of the heater and the plates of said rectifier being connected to the ends of said heater, said device having five prongs, 130 two of the prongs being connected to the terminals of the heater and the plates of said rectifier being connected to the ends of said heater.

the rectifier, one of said prongs being connected to the center point of the heater, one of said prongs being connected to the cathode of the audion, and the remaining prong 5 being connected to the grid of the audion, whereby the grid and cathode of the audion may be connected to an input circuit, and the cathode of the audion and the center point of the heater may be connected to an 10 output circuit.

5. A unitary electron discharge device comprising an evacuated vessel having a full wave rectifier provided with a pair of plates and a cathode, a current limiting device provided with a plate and a cathode, 15 the plate of the current limiting device be-

ing connected to the cathode of the rectifier, and an audion having a plate and a cathode and an interposed grid, the plate of the audion being connected to the cathode of 20 the current limiting device, a heater for said cathodes, and a connection leading to the center point of the heater, the plates of the rectifier being connected to opposite ends of 25 said heater, and a bypass condenser between the plate of the audion and the center point of the heater.

In testimony that I claim the foregoing I have hereunto set my hand at Milwaukee, 30 in the county of Milwaukee and State of Wisconsin.

ARISTOTE MAVROGENIS.
